SAFETY DEVICE FOR SEAPLANES

John Parkeson Reynolds, Buffalo, N. Y.

Application July 2, 1943, Serial No. 493,272

1 Claim. (Cl. 244—2)

This invention aims to provide a novel means whereby a flying boat may be denuded of its wings and tail structure, after the hull of the boat has landed on the surface of the water.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Fig. 1 shows in top plan, a device constructed in accordance with the invention;

Fig. 2 is a side elevation;

Fig. 3 is a top plan wherein the wings and associated parts are omitted;

Fig. 4 is a cross section on the line 4—4 of Fig. 3;

Fig. 5 is a vertical sectional view showing the cushioning and return means for the movable portions of the track rails;

Fig. 6 is a fore and aft section showing the winch;

Fig. 7 is a thwartship section showing the winch.

The flying boat forming the subject matter of this application comprises a hull 1 of any desired construction, the deck appearing at 2, the marine propeller at 3, the skeg at 4, the rudder post at 5, and the rudder at 6, a part of the stern frame being marked by the numeral 7.

Fore and aft, parallel track rails 8 are secured at 9 to the deck 2 and terminate at the after end of the deck.

Track extensions 10 have their forward ends pivoted at 11 to the after ends of the rails 8, for up and down swinging movement. The extensions 10 normally are aligned axially with the rails 8 but may have an up and down swinging movement. The means for holding the extensions 10 in the position specified, and for permitting them to yield downwardly, will now be described.

The numeral 12 designates a frame, secured at 14 to the after portion of the hull 1, and held in that position by braces 15, connected to the stern of the hull 1.

Figures 2 and 5 disclose a combined lifting and

cushioning device 16, comprising upright cylinders 17 having their lower ends pivoted at 20 to the frame 12. Plungers 18 are mounted for reciprocation in the cylinders 17, compression springs 19 being interposed between the bases of the cylinders and the lower ends of the plungers 18. The upper portions of the plungers 18 are pivoted at 21 to the track extensions 10.

The numeral 22 marks a wing structure carrying aerial propellers 52.

Figure 3 shows a U-shaped truck 23, which is made up of side beams 24, in the form of inverted channels, the side beams being parallel, and being secured at 25 to the bottom portions of the wings 22. At their after ends, the side beams 24 of the truck 23 are rigidly connected by a cross bar 26. The channel-shaped side beams 24 of the truck are mounted to slide on the track rails 8 and their extensions 10, fore and aft. Nuts 27 are welded to the upper parts of the channel beams 24 and may be considered as parts thereof.

The channels 24, being secured to the wings 22, and being engaged with the track rails 8 on the deck 2, prevent the wings from shifting thwartship. The means for preventing the wings 22 from shifting fore and aft is shown best in Fig. 4.

Hand screws 28 are mounted to rotate in the deck 2 and in the rails 8, which are secured to the deck, but they are threaded into the nuts 27 on the channel-shaped truck beams 24. Lock nuts 29 are mounted on the screws 28 and clamp the entire wing structure to the deck 2. L-shaped stops 30 are secured to the deck 2 and extend downwardly and laterally, under the lock nuts 29.

A tail structure 31, of any desired form, or of conventional make-up, is united by rearwardly converging connections 32 with the side beams 24 of the truck 23.

Parallel, fore and aft fluid pressure cylinders 33 are secured at 34 to the deck 2 and are open at their rear ends, as shown in Fig. 3 at 35. Piston structures 36 are mounted for reciprocation in the cylinders 33 and are pivotally connected at their after ends, as shown at 37, with the cross bar 26 of the truck 23. The forward ends of the cylinders 33 are connected by a U-shaped header 38. The intermediate portion of the header 38 is in communication with a conduit 39, extending downwardly into the hull 1 and connected to a source 40 of fluid pressure supply, a valve 41 under the control of the operator being interposed in the conduit.

A drum 42 is mounted at 43 on the stern frame

7 and carries a line 44, extended rearwardly through a guide 46 in the stern frame 7 and thence forwardly along the deck 2, the line terminating in a hook 45. The drum 42 may be operated by a crank 47, or any other suitable means. The line 44 may be connected, detachably, through the instrumentality of the hook 45, with a ring 49 on the forward part of the wing structure 22.

The screws 28 are rotated until they are clear of the nuts 29 on the truck beams 24. This sets the wings 22 free for rearward sliding movement. As the screws 28 are backed off, the nuts 29 come into contact with the stops 30 and then the operator knows that the wings 22 and their tracks 24 are free to slide aft. By means of the valve 41 of Fig. 2, pressure is admitted to the conduit 39, and thence into the forward ends of the cylinders 33, by means of the header 38.

The piston structures 36 are moved astern, carrying with them the truck 23 and the wing structure 22 which is connected thereto. Ultimately, the piston structures 36 move out of the cylinders 33, through the open, after ends 35 of the cylinder.

Ultimately the truck 23, represented sufficiently by the side beams 24, slides upon the extensions 10 of the track rails 8. Under the weight of the wing structure 22, the extensions 10 swing downwardly on their pivots 11, thus easing the wings down upon the sea. Referring to Fig. 5, as the extensions 10 swing downwardly, the plungers 18, cooperating with the springs 19 cushion the downward swinging movement of the parts 10. The wings 22 are deposited on the water, at a mild angle to the surface thereof, and are not plunged downwardly, edgewise, into the water. After the wings 22 and associated parts are deposited on the surface of the water, the springs 19 of Fig. 3 react on the plungers 18, to dispose the extensions 10 into horizontal position.

The hull 1 of the boat now is free from the wing structure 22, saving for the line connection 44, and the connection is paid off the drum 42, to any desired extent to serve as a tow line for the

wing structure 22. If there is a high sea running, or if for any other reason it is desired to have the boat unencumbered by a tow, the hook 45 can be cast off the ring 49 on the wing structure 22.

5 The deck 2 is smooth from the after end of the cylinder 33 to the extreme after end of the deck, to permit the piston structure 36 to move readily thereover, after the piston structure has left the cylinder. When the truck 23 and the wings 10 22 are clear of the hull 1, the piston structure depends from the truck and forms a drag, adapted to foul the bottom in shallow water, or on a shoal. The wing structure is anchored, to some extent, and perhaps completely, depending upon 15 the nature of the bottom. The wing structure may be prevented from becoming beached and pounded to pieces in the breakers. At least, the progress of the floating wing structure will be slowed up, an opportunity being afforded to salvage it. The 20 piston is not without function as to drogue.

The boat, especially if it has abandoned its wing structure 22, may be used for transportation purposes, such as landing troops and the like.

Having thus described the invention, what is 25 claimed is:

In a safety device for sea planes, a sea plane hull including a deck, a fore and aft track on the deck and extended to the stern thereof, a wing, a truck secured to the wing and mounted to move 30 along the track, power means for moving the truck and the wing astern and clear of the hull, the power means comprising a fluid pressure cylinder mounted on the deck and a piston structure slidable in the cylinder, and means for pivoting the piston structure to the truck for vertical swinging movement, the cylinder being open at its after end, to permit the piston structure to depart from the cylinder as the piston structure moves the truck and the wing astern, 35 40 the deck being smooth from the after end of the cylinder to the extreme after end of the deck, to permit the piston structure to move readily thereover, the piston structure forming a drag for the wing when the wing is clear of the hull.

JOHN PARKESON REYNOLDS.
